UNITED STATES PATENT OFFICE.

JOHN CONLIN AND ROBERT WHITTY, OF RIPON, WISCONSIN.

SHOW-CASE.

SPECIFICATION forming part of Letters Patent No. 557,974, dated April 7, 1896.

Application filed December 9, 1895. Serial No. 571,512. (No model.)

To all whom it may concern:

Be it known that we, JOHN CONLIN and ROBERT WHITTY, of Ripon, in the county of Fond du Lac and State of Wisconsin, have invented a new and Improved Show-Case, of which the following is a full, clear, and exact description.

The object of the invention is to provide a new and improved show-case which is simple and durable in construction, more especially designed for exhibiting cigars and like articles, and arranged to permit the shopkeeper to open the case in such a manner as to enable a preferred customer to select and remove the desired goods or to keep the case closed to other customers and open only so that the shopkeeper can take out the goods.

The invention consists principally of a casing provided with a cover hinged to a frame mounted to swing.

The invention also consists of certain parts and details and combinations of the same, as will be fully described hereinafter, and then pointed out in the claims.

Reference is to be had to the accompanying drawings, forming a part of this specification, in which similar characters of reference indicate corresponding parts in all the figures.

Figure 1 is a perspective view of the improvement with parts in a closed position. Fig. 2 is a like view of the same with the cover open to the customer. Fig. 3 is a rear elevation of the improvement, and Fig. 4 is a transverse section of the same on the line 4-4 of Fig. 3.

The improved show-case is provided with a casing A, formed with an inclined front A', on which is adapted to rest an open frame B, connected at its lower end by hinges C with the lower end of the front A'. On the upper end of the frame B are arranged hinges D, connected with the cover E, having a pane of glass to permit of viewing the contents of the box A from the outside. The cover E may be flat or arched, as indicated in the drawings.

The goods to be displayed are arranged on shelves F, held within the casing and arranged in step form, as plainly indicated in the drawings. The shelves are preferably constructed with two stringers F', supporting bottom boards F² and risers F³, each bottom board and riser being provided with lugs F⁴, resting

against the inner faces of the two stringers, to prevent the bottom boards and risers from shifting laterally.

55

The stringers F' abut at their lower and upper ends on blocks F⁵ and F⁶, secured in the casing, and said stringers are held in place on the blocks by pivoted catches F⁷, engaging opposite sides of the blocks F⁵ and F⁶. By 60 this arrangement the shelves F can be readily removed whenever desired to permit of conveniently cleaning the casing when necessary.

In order to impart an upward swinging motion to the cover E, we connect the side bars 65 of said cover E by links G with arms G', extending from a shaft H, journaled in suitable bearings formed in brackets I, secured within the casing A under the shelves F. (See Fig.

4.) On the shaft H is secured a beveled gear-wheel H', in mesh with a beveled gear-wheel J', secured on the inner end of a shaft J, journaled in suitable bearings in a bracket I' and in the back A² of the casing E. On the outer end of the shaft J, which extends a suitable 70

distance beyond the back A², is secured a spring-arm J², provided near its free end with a lug J³, adapted to engage one of a series of notches formed on a segmental rack K, attached to the back A².

75

In order that the frame B and cover E may be opened by the shopkeeper, we pivotally connect the sides of the frame B near their upper ends by links L with arms L', secured on a shaft N, journaled in the bracket I. On the 85 shaft N is secured a gear-wheel N', in mesh with a beveled gear-wheel O', secured on a transversely-extending shaft O, journaled in the bracket I' and in the back A² of the casing. On the outer end of the shaft O is secured a spring-arm O², adapted to engage a notched 90 segment K' similar to the segment K hereinbefore described.

Now it will be seen that when the several parts are in the position shown in Figs. 1, 3, 95 and 4 then the arm J² is in a lowermost position on the segmental rack K and the cover E is in a closed position. Now when it is desired to swing the said cover E upward into an open position then the operator turns the 100 arm J² upwardly, so that a turning motion is given to the shaft J, which, by means of the gear-wheels J' and H', rotates the shaft H, so that the arms G' held on said shaft swing up-

ward and by means of the links G impart an upward swinging motion to the cover E. The latter is thus opened to the customer standing in front of the show-case to permit him to select and remove the desired article displayed on the shelves F. When this has been done, the shopkeeper turns the arm J² downward, back to the former position, so that the cover E swings into a closed position.

10 When the shopkeeper desires to remove the displayed articles from the casing and without desiring the customer to handle the goods while in the casing, the shopkeeper turns the other arm O² in an upward direction to cause the shaft O to turn. The motion of this shaft is transmitted by the gear-wheels O' and N' to the shaft N, which causes the arms L' to swing forwardly, so that the links L impart a forward swinging motion to the frame B, which latter turns on the hinges C and carries along the cover E. Thus the casing is still closed to the customer in front, but is open to the shopkeeper to permit him to remove the goods desired by the customer. When 25 this has been done, the shopkeeper swings the arm C² downward back to its former position to cause the frame B to swing back to place and at the same time close the cover E.

It is understood that the arm J² when in 30 its lowermost position is free to swing a suitable distance before striking the notches in the segment K, so that when the frame B is swung outward, as previously described, and the cover E moves along with the frame, then 35 the motion given to the links G, arms G', shafts H and J, and their gear-wheels H' and J' is not interfered with, as the arm J² is in an unlocked position.

The interior of the casing A is lined with 40 zinc and is adapted to receive a sponge or other moistening device in case cigars or tobacco are displayed on the shelves. By having the notched segments K and K' we are enabled to hold either the frame B or the 45 cover E in any desired angular position.

Having thus fully described our invention, we claim as new and desire to secure by Letters Patent—

1. A show-case comprising a casing having an inclined front, a frame adapted to be seated on said front and hinged to the lower end thereof, a cover hinged to the upper end of said frame and adapted to be seated thereon, and mechanisms for imparting swinging motions to said frame and said cover, to open the casing, substantially as shown and described.

2. In a show-case, the combination of a casing, a frame hinged on said casing, a cover hinged to said frame, and mechanism for independently swinging the cover and frame, substantially as described.

3. In a show-case, the combination with a casing, of a frame hinged thereto, a cover hinged to the frame, and means for moving the frame to swing with the cover and for independently moving the cover, substantially as described.

4. In a show-case, the combination with a casing, of a frame hinged to the casing, a cover hinged on the frame, mechanism for independently moving the cover and the frame, arms respectively operating said mechanism, and ratchet-plates by which the arms may be held, substantially as described.

5. In a show-case, the combination with a casing, of a frame hinged thereon, a cover hinged to the frame, two shafts, a link connection between each shaft and the respective cover and frame, a second shaft geared with each of the first shafts, an arm carried by each of the second shafts, and a ratchet-plate for each arm, substantially as described.

6. In a show-case, the combination with a casing, of a cover hinged thereon, a shaft, a link connection between the shaft and the cover, a second shaft geared with the first, an arm carried by the second shaft, and a ratchet-plate with which the arm co-operates, substantially as described.
